ATTORNEY:

UNITED STATES PATENT OFFICE

167,520

PAPER PUNCH OR SIMILAR ARTICLE

Herbert W. Marano, Brooklyn, N. Y., assignor to Wilson Jones Company, Chicago, Ill., a corporation of Massachusetts

Application April 24, 1952, Serial No. 19,453

Term of patent 14 years

(Cl. D74—1)

To all whom it may concern:

Be it known that I, Herbert W. Marano, a citizen of the United States, and a resident of Brooklyn, New York, have invented a new, original, and ornamental Design for a Paper Punch or Similar Article, of which the following is a specification, reference being had to the accompanying drawing, forming a part hereof, in which

Figure 1 is a top plan view of a paper punch, or similar article, showing my new design;

and

Figure 3 is a side elevational view thereof.

I claim:

The ornamental design for a paper punch or similar article, as shown.

HERBERT W. MARANO.
